SEWING MACHINE WORK SUPPORT

Louis G. Bowman, St. Louis, Mo., assignor to
 Lewis Invisible Stitch Machine Company, St.
 Louis, Mo., a corporation of Maine

Original application September 27, 1935, Serial
 No. 42,547. Divided and this application May
 5, 1936, Serial No. 78,035

16 Claims. (Cl. 112—260)

This invention relates to new and useful improvements in sewing machines generally, although more particularly to the work support of a blind stitch sewing machine.

5 This application constitutes a division of my co-pending application Serial No. 42,547, filed Sept. 27, 1935, for improvements in Sewing machines.

The principal object of this invention is to provide a novel depressible work support and yieldable dual spring mounting therefor whereby a relatively strong resistance to depression of the support is offered during normal sewing operations and a relatively weaker resistance to depression of the support is encountered by an operator when inserting a fabric in the machine or when removing the fabric therefrom.

With the above and other objects in view which will more fully appear, the nature of the invention will be more clearly understood by following 20 the description, the appended claims, and the several views illustrated in the accompanying drawings.

In the drawings:

25 Figure 1 is a front elevation of a sewing machine embodying my invention,

Figure 2 is a top plan view thereof,

Figure 3 is a partial right hand elevation of the machine, and

30 Figure 4 is a detail vertical sectional view illustrating the dual spring mounting of the work support.

Like reference numerals designate corresponding parts throughout the several figures of the drawings.

35 My invention is disclosed as being applied to a blank stitch sewing machine which embodies a main frame having a base 5, a standard 6, and a laterally extending arm 7 which terminates in a forwardly extending stitching head 8. A main shaft 9 is journaled in the laterally extending arm 7 and the upper end of the standard. A horizontal presser foot 20 is rigidly attached to the front end of the forwardly extending head 8. An oscillatory needle 24 and a cooperating stitch forming mechanism are supported on the head 8 and are operatively connected to the main shaft 9.

40 A work support or table 41 is pivotally supported at 42 on a horizontal shaft 43 supported in and extending laterally from the frame standard 6 in parallelism with the main shaft 9. The support 41 includes an upstanding guard flange portion 44 and a slightly depressed portion 45 which extends laterally from said support be-

neath the presser foot 20 as shown in Figures 1 and 2.

A lug 126 depends from the work support 41 and to this lug a latch dog 127 is pivoted as at 128. The dog 127 includes an eccentric lock surface 129 and a release lug extension 130. The lock surface 129 normally rests on the horizontal leg 131 of a bell crank lever pivoted at 132 on the frame lug 133, the remaining leg 134 of the bell crank extending downwardly and engaging a strong cushion spring 135 seated in a frame socket 136. The contact between the leg 134 and the spring 135 is made by an adjustable abutment screw 137.

By reason of the direct contact between the parts 129, 131, 137, 135 downward movement of the work support 41 is strongly resisted by the spring 135 and the tendency of the spring 135 to force the support upwardly is suitably resisted by an adjustable stop screw 138 threaded through the guard wall 44 and abutting a stop 139 secured on the frame standard. By provision of this equipment a downwardly yieldable work support is provided and yet the spring 135 is much too strong to permit undesirable downward movement thereof.

When it is desired to lower the support 41 to insert or remove the work, the operator should not be subjected to the severe labor and strain necessary to oppose the relatively stronger spring 135 and for this reason I have provided a relatively lighter spring and means whereby the strong spring may be rendered ineffective and the weaker spring brought into play simultaneously with the effort of lowering the support.

It will be observed by reference to Figure 4 that a coil spring 140 connected to the support 41 and the dog 127 serves normally to retain the dog in the position illustrated in Figure 4. The relatively weaker spring above referred to is in the nature of a coil spring 141 coiled about the stud 142 projecting from the frame lug 133 and having one end thereof anchored as at 143 to the frame and the other end 144 engaging under the work support 41 as shown in Figure 4. A trip lever 145 is pivoted intermediate its ends as at 146 to a lug depending from the support 41. One end of the lever projects under the release lug 130 and to the remaining end a pull chain 147 is secured. By pulling downwardly on the chain 147 the dog 127 will be tripped to the position illustrated in dotted lines in Figure 4, thus releasing the support 41 from the influence of the relatively stronger spring 135 and permitting the operator to lower the support by use of the chain 55.

147 resisted only by the relatively weaker spring 141. Upon release of the chain the spring 140 will return the dog 137 to the position illustrated in full lines in Figure 4, the eccentric surface 129 5 facilitating the return to normal engagement with the bell crank leg 131.

The strong spring 135 is essential to the attainment of even needle penetrations because the needle travels in a fixed path and consequently 10 the same depth of the ridge of material must be always presented to the needle. Thus in the formation of "anchor" stitches it is necessary that the ridge forming element rise to the same high position in relation to the needle, and the 15 work support which carries the element must be substantially rigid when heavy seams are encountered. The resistance to upward movement of the element must not be solid, however, because if the element could not push the material up through the opening in the presser foot 20 something must yield or break. The spring 135 provides the desirable strong yet yieldable resistance.

When the operator desires to insert work, a 25 slight pull on the chain 147 will release the toggle 145, 127. With the parts in this position the light spring 141 alone is effective to hold the work support against depression and only a slight force is necessary to be exerted by the 30 operator to depress the work support 41 sufficiently for inserting the work under the presser foot, or removing work therefrom. In this manner the depression of the work support or table 41 may be said to be opposed by a primary means 35 and a secondary means of varying degree, and that said means may be rendered selectively dominant.

A stop screw 148 is provided to maintain a working contact between the cam surface of 40 the latch dog 127 and the nose of the leg 131 of the bell crank lever.

It will be seen that the lock surface 129 of the latch dog 127 and the leg 131 of the bell crank lever, constitute a means which includes thrust 45 applying and releasing elements which are changeable in relation from depressive thrust applying position as shown in Fig. 4 by the full lines, to depressive thrust releasing position as shown in Fig. 4 by the dotted lines.

50 It is of course to be understood that the details of structure and arrangement of parts may be variously changed and modified without departing from the spirit and scope of my invention.

I claim:

55 1. In a sewing machine, the combination of a deppressible work support, means for imposing upon the support a primary degree of resistance to depression, means for imposing upon the support a secondary degree of resistance to depression, and means for rendering said primary and secondary resistance imposing means selectively dominant.

2. In a sewing machine, the combination of a deppressible work support, normally effective 65 means including a relatively strong spring for yieldingly retaining the support against depression, means including a relatively weak spring for retaining the support against depression when said normally effective means is rendered ineffective, and means for rendering said normally effective 70 means ineffective.

3. In a sewing machine, the combination of a deppressible work support, normally effective means including a relatively strong spring for 75 yieldingly retaining the support against depression,

means including a relatively weak spring for retaining the support against depression when said normally effective means is rendered ineffective, and means for first rendering said normally effective means ineffective and for thereafter depressing the support against the tension of the weaker spring. 5

4. In a sewing machine, the combination of a deppressible work support, means including a relatively strong spring for imposing upon the support a primary degree of resistance to depression, means including a relatively weak spring for imposing upon the support a secondary degree of resistance to depression, and means for rendering said primary and secondary resistance imposing means selectively dominant. 10

5. In a sewing machine, the combination of a frame including a stitching head, a stitch forming means including a reciprocable needle mounted on the head, a deppressible work support mounted on the frame and disposed below said head, means for imposing upon the support a primary degree of resistance to depression, means for imposing upon the support a secondary degree of resistance to depression, and means for rendering said primary and secondary resistance imposing 20 means selectively dominant. 25

6. In a sewing machine, the combination of a frame including a stitching head, a stitch forming means including a reciprocable needle mounted 30 on the head, a deppressible work support mounted on the frame and disposed below said head, normally effective means including a relatively strong spring for yieldingly retaining the support against depression, means including a relatively weak spring for retaining the support against depression when said normally effective means is rendered ineffective, and means for first rendering said normally effective means ineffective and for thereafter depressing the support 40 against the tension of the weaker spring. 35

7. In a sewing machine, the combination of a frame including a base, a standard, and an overhanging arm; a stitching head carried by the arm; stitch forming means including a reciprocable needle; a deppressible work support pivotally supported on said standard and extended beneath said head; normally effective means including a relatively strong spring for yieldingly retaining the support against depression; means including 45 a relatively weak spring for retaining the support against depression when said normally effective means is rendered ineffective; and means for rendering said normally effective means ineffective. 50

8. In a sewing machine, the combination of a frame including a base, a standard, and an overhanging arm; a stitching head carried by the arm; stitch forming means including a reciprocable needle; a deppressible work support pivotally supported on said standard and extended beneath said head; normally effective means including a relatively strong spring for yieldingly retaining the support against depression; means including a relatively weak spring for retaining the support against depression when said normally effective means is rendered ineffective; and means for first rendering said normally effective means ineffective and for thereafter depressing the support 60 against the tension of the weaker spring. 65

9. In a sewing machine, the combination of a deppressible work support, means including thrust applying and releasing elements changeable in relation from depressive thrust applying to depressive thrust releasing position for resisting or 70 75

- permitting depression of the support, light spring means for resisting depression of the support when said elements are in thrust releasing position, and means to move said elements.
5. 10. In a sewing machine, the combination of a depressible work support, means including thrust applying and releasing elements changeable in relation from depressive thrust applying to depressive thrust releasing position for resisting or 10 permitting depression of the support, light spring means for resisting depression of the support when said elements are in thrust releasing position, and means for changing the relation of said elements to negate their resisting function and to 15 depress the support against the tension of said spring to change their relation.
11. In a sewing machine, a frame, a depressible support mounted on the frame, a relatively strong spring, make and break thrust connections in- 20 terposed between the strong spring and the support to normally offer strong yieldable resistance to depression of said support, means to break the connections and the strong resistance to depression of the support, and a weak spring effective 25 to resist depression of the support when said connections are broken.
12. In a sewing machine, a frame, a depressible support mounted on the frame, a relatively strong spring, a thrust lever pivoted to the frame and 30 engaging the strong spring, a thrust link pivotally supported on the support and movable into and out of engagement with the lever to respectively impart depressive thrusts to the lever and the strong spring or to relieve the support of the 35 resistance of said strong spring, and a weak spring effective to resist depression of the support when the link and lever are disengaged.
13. In a sewing machine, a frame, a depressible support mounted on the frame, a relatively strong 40 spring, a thrust lever pivoted to the frame and engaging the strong spring, a thrust link pivotally supported on the support and movable into and out of engagement with the lever to respectively impart depressive thrusts to the lever and the strong spring or to relieve the support of the 45 resistance of said strong spring, a weak spring effective to resist depression of the support when

the link and lever are disengaged, and means for moving the link out of engagement with the lever and for depressing the support.

14. In a sewing machine, a frame, a depressible support mounted on the frame, a relatively strong spring, a thrust lever pivoted to the frame and engaging the strong spring, a thrust link pivotally supported on the support and movable into and out of engagement with the lever to respectively impart depressive thrusts to the lever and the strong spring or to relieve the support of the resistance of said strong spring, a weak spring effective to resist depression of the support when the link and lever are disengaged, means for moving the link out of engagement with the lever and for depressing the support, and means to automatically restore link and lever engagement when the depressing force on the support is released.

15. In a sewing machine, the combination of a depressible work support, means for imposing upon the support a primary degree of resistance to depression, means for imposing upon the support a secondary degree of resistance to depression, means for rendering said primary and secondary resistance imposing means selectively dominant, and adjustable means cooperating with said primary resistance imposing means for adjusting the extreme upward limit of movement of the work support.

16. In a sewing machine, a frame, a depressible support mounted on the frame, a relatively strong spring, a thrust lever pivoted to the frame and engaging the strong spring, a thrust link pivotally supported on the support and movable into and out of engagement with the lever to respectively impart depressive thrusts to the lever and the strong spring or to relieve the support of the resistance of said strong spring, a weak spring effective to resist depression of the support when the link and lever are disengaged, means for moving the link out of engagement with the lever and for depressing the support, and means for limiting freedom of movement of the lever during disengagement of said lever and link.

LOUIS G. BOWMAN.
